NONSKID SHOE ATTACHMENT

James Henry Mercer and Jack Jones, Baltimore,
Md., assignors of thirty-three and one-third
per cent to Charles E. Watts, Baltimore, Md.

Application May 2, 1936, Serial No. 77,493

2 Claims. (Cl. 36—7.6)

This invention refers to shoes and more particularly to attachments for the shoes or boots of loggers, to enable them to stand securely on logs and other rugged surfaces. It has, among 5 its objects, the provision of a flexible, light, yet strong attachment that may be securely fastened to the shoes or boots of the user, to enable him to walk, roll, or stand on floating or stationary logs and surfaces with safety.

10 Devices have been used in the past to prevent slipping on conventional road surfaces and are called creepers, but these do not meet the conditions arising in logging. The loggers are compelled to "ride" timber logs of all sizes and conditions and positions. The use of creepers for this purpose does not suit the situation. Applicant's device, by reason of being preferably made of wire construction, provides a flexible shoe that will resiliently bend and give to suit any 15 of the conditions, while the spikes provided on projecting ends of the wire serve to dig into the logs or surfaces securely. They also cover the whole surface of the bottom of the shoe and yet are light. The heel portion is arranged to 20 grip the heel and back of the logger's shoe or boot, to allow the leg of the user to exert a desirable leverage for detaching or inserting the spikes, as well as bend the wire framing to suit the contour of the logs, or surfaces. The spikes 25 also have a springing action which serves to prevent their breaking off, afford a better frictional action, and more quickly disengage.

In the construction shown in the drawing:

Figure 1 is a general plan view of logging shoe 30 attachment looking down on the upper and inner side of same.

Figure 2 is a sectional elevation along the line 2—2 of Figure 1.

Figure 3 is a view along the line 3—3 of Figure 40 1, and

Figure 4 is a view along the line 4—4 of Figure 1. Similar reference characters refer to similar parts throughout the drawing.

A frame 1 preferably of wire is formed to the 45 general conventional shape of the sole of a shoe or boot, with its toe portion 2 rounded; the ball-of-the-foot portion 3 relatively wide; narrowing at the instep portion 4; and with a heel-outline portion 5 formed at the rear where a twisted 50 joint connection 6 is provided.

A series of cross-wire braces 7 run across the frame as indicated, being twisted around the side wires of same with loops 8, which end with down-pointing spikes 9, sharpened and arranged to stick 55 into the wood of logs, timber, etc. with some

resiliency. The braces are more numerously and closely placed on the sole portion of the frame, to take up the wear where it is normally greatest. A center member 10 of wire is provided to reinforce the braces and stiffen the whole frame. 5 This center member is tied-in with the braces through the coils 11 twisted around it, as shown. The center member extends from the tip of the toe portion to the front of the heel, and is given a slight bend to conform with the left or right outline of the foot; and assist in the action of the device. A heel chair 12 is arranged above the main plane of the frame 1, and bends around so as to engage the heel of the shoe or boot of the user, starting at its uprights 13 disposed near the front of the heel. Additional uprights 14 coiled about the wire of the heel chair and frame 1 serve to resiliently strengthen this portion. 10

Straps 15 are provided for securing the frame 20 to the front portion of the user's shoe, and straps 16 for the portion close to the heel. With this arrangement of two sets of straps as indicated and the heel chair for the heel, the device can be substantially and rigidly attached. 25

It should be noted that the frame is flat across the bottom of the shoe and is unbroken from toe to heel. This enables the device to be stamped down on a log, and any "give" near the middle due to the curvature of the log, etc. tends to make the frame hold tighter onto the shoe of the user. On relieving this pressure, there is a tendency for the spikes to lift out. This action may be made clearer by analyzing the movement of the sole of the frame with its spikes. When the sole of the 30 attachment is laid flat on a flat surface its spikes are disposed perpendicularly downwards and tend to enter the surface at right angles to it. If, however, the surface is convexly curved, the wire frame is bent around same more or less, 35 which brings the spikes around radially projecting into same. If the foot is moved in either direction, it will press the spikes like a fish-hook on one part of the arc into the surface, and make the attachment more tightly attached to same. 40 This continues as long as the sole is bent or arched. This same action is also true of all spikes of the coils 11, a feature which enables the logger to run on the logs, or roll them, without catching or locking the spikes in the same. It permits 45 quick and active movement on the part of the user, while effectively preventing him from losing his grip on the log, or other surface, sufficiently to cause him to slip off. The variation in the surfaces walked on by the logger is taken up by the 50 55

device through its natural tendency to bend or warp to suit same. Since the device is held on securely and cannot move relatively with the shoe, it affords a very tightly held-on device that cooperates thoroughly with the skill of the user and gives him a very desirable confidence in its use. The center member 10 is very effective in reinforcing the frame as well as preventing it from losing its shape, as it holds the braces in place, and the toe 2 from lengthening out.

10 While but one form of the invention is indicated in the drawing it is not desired to limit this application for patent to this particular form, otherwise than limited by the prior art, as it is appreciated that other forms of construction could be used that would employ the same principles and come within the scope of the appended claims.

15 Having thus described the invention, what is claimed is:

20 1. A device of the class described comprising in combination a flat sandal wire frame formed in the outline of the sole of a foot, a central member of wire secured to the toe portion of the outline and passing therefrom down the middle of the frame and stopping in front of the heel portion, a 25 plurality of wire braces transversely disposed across the side of the frame and entwined about the wires of the sides and central member and spaced in close proximity to each other to

divide the ball portion of the frame into a relatively large number of sections, a plurality of spikes extending downwardly from said braces, a plurality of braces for the heel portion of the frame having spikes extending therefrom, a heel 5 saddle of wire for holding the heel of a shoe, and foot attaching means at the heel and toe portions of the frame.

2. A device of the class described comprising in combination a flat sandal wire frame formed in the outline of the sole of a foot, a central member attached to the toe portion thereof and looped over to provide a resilient toe spike, and its other end portion terminating in front of the heel portion and twisted into a loop, a plurality of spaced 10 wire braces extending in close array from side to side of the frame and with their end portions looped around the said sides and extending down as spikes therefrom, and their middle portions looped around the central member, one of the 15 braces being looped by the end portion of the central member, a plurality of spaced braces at the heel portion having their end portions extending downwardly as spikes therefrom and loops formed by the braces engaging the wire 20 frame sides, and foot holding straps attached to the frame at the heel and toe portions thereof.
